UNITED STATES PATENT OFFICE.

WILLIAM C. COLLYER, OF READING, MASSACHUSETTS, ASSIGNOR OF ONE-THIRD TO WILLIAM H. PERKINS, OF SAME PLACE.

SEWING-MACHINE FOR LASTING BOOTS OR SHOES.

SPECIFICATION forming part of Letters Patent No. 516,695, dated September 24, 1895.

Application filed November 19, 1894. Serial No. 529,234. (No model.)

To all whom it may concern:

Be it known that I, WILLIAM C. COLLYER, of Reading, in the county of Middlesex and State of Massachusetts, have invented certain new and useful Improvements in Machines for Uniting Uppers and Soles of Boots or Shoes, of which the following is a specification.

This invention relates to machines for uniting uppers and soles of boots and shoes, and has in view for one thing an improved arrangement of last-supporting jack whereby the operator is enabled to hold the last in any position required, and at the same time an automatic-feed mechanism may be applied to the jack.

Another object of the invention is to provide an improved arrangement of stitch-forming and lasting devices on a universally-movable support under control of the operator, which arrangement, together with that of the jack, enables the operator to work close to the last all the time, and therefore turn out a perfectly-sewed shoe.

The invention involves numerous combinations of parts, all of which will be found recited in the appended claims.

The invention is illustrated in the accompanying drawings, of which—

Figure 1 shows the complete machine in side elevation. Fig. 2 shows it in plan. Fig. 3 shows it in front elevation. Fig. 4 shows a section on line 4 4 of Fig. 3 on an enlarged scale. Fig. 5 shows a section on line 5 5 of Fig. 2. Figs. 6 and 7 show sections on lines 6 6 and 7 7, respectively, of Fig. 5. Fig. 8 shows a section on line 8 8 of Fig. 4. Fig. 9 shows a perspective view of a portion of a partly-sewed shoe, together with certain parts of the machine which directly engage the work.

The letter *a* designates a supporting-column made in sections, with screw-threads at *a'* to secure vertical extensibility, and its upper movable section supporting a horizontally-extending platform *a''*. On this upper section of the column there is swiveled a head *a''*, between projecting arms of which a frame *a''* is pivoted to swing vertically to a limited extent, the said frame carrying stitch-forming and lasting devices and the frame and head forming a universally-movable support, which

the attendant controls by means of a handle *g*. The journal of the frame *a''* is a shaft *b*, which carries a clutch member *b'* and a cam-grooved cylinder *b''*, and at the forward part 55 of the frame there is a transversely-sliding tubular rod *b'''*, having affixed to it a collar *b'''*. A horizontally-swinging lever *b''''* is pivoted to an ear of the frame and carries a roller-equipped pin at one end in the groove of the 60 cylinder *b'''*, and at the other end is connected by a link *b''''* with the collar *b'''*. A standard *c*, erected on the frame, supports a quadrantal rocker *c'*, and there is a lever *c''* suspended from one end of said rocker and slotted to 65 embrace the rod *b'''*. The said lever at the upper end of its slot fits between two lugs of a bracket *c''''*, fastened to the collar *b'''*, and in the reciprocations of said collar, received through vibration of the lever *b''''* by the cam 70 *b''*, the lever *c''* is oscillated.

A curved needle *c''''* is fastened in a holder *c'''''*, formed on the lower end of the lever *c''*, and the oscillations of the lever take the needle through the work which is held for it in a 75 manner hereinafter described. A bifurcated guide *d* depends from a bracket *d'* on the frame and receives a lip of the inner sole in its bifurcation, (see Fig. 9,) and is notched in the rear side to accommodate the needle. A 80 slotted presser-foot *c''''* bears against the upper and holds it against the guide *d* and is pivoted to a bracket *c'''''* on the frame and held by a spring *c'''''* against the work. The pivot of the presser-foot *c''''* is extended downward to support a conical rest *u* for the upper to bear against where it lies over the side of the last, this conical rest sustaining the last laterally. The needle passes through the slot of the presser-foot and the notch of the guide *d* and 85 has a suitably-located barb to engage the thread 2, which runs through an eye in the end of a hook-shaped thread-guide *e*, located on the outer side of the lip-guide *d*. Said thread-guide is fastened in an arm *e'*, affixed to a shaft *e''*, which is journaled in a bearing on the frame and carries a crank-arm *e'''*. The latter is jointed to an arm *e'''*, of an eccentric strap *e''''*, embracing an eccentric *e'''''* on the shaft *b*. Through these connections it will be seen 90 that an up-and-down vibration of the thread-guide is obtained. In the downward move-

ment the thread is engaged with the needle, and in the upward movement the thread-guide acts as a take-up to tighten the stitch. The ordinary chain-stitch is used, and is so common in the art as to need no further explanation.

In conjunction with the needle, lasting-pinchers are arranged to operate on the upper, and they have in addition to their opening-and-closing movement an up-and-down and also lateral movement, so that they may be caused to move down and inward when open to position for grasping the work and then grasp the work and move up and outward to stretch the upper over the last and hold it so while the needle penetrates it. One member f of the pinchers is connected at its upper end through a link f' with the quadrantal rocker c' , and by a link f'' with the pendent portion of the bracket d' , and the other member f^2 , which is pivoted to the member f , is connected by a link f^3 with a rod f^4 , fitting through the tube b^3 . Said rod f^4 is slotted to receive a pin f^5 (see Fig. 5) fastened in the tube, and there is a spiral spring f^6 surrounding the rod between a shoulder thereof and the said pin, so that movement of the tube is transmitted to the rod through this spring. The object of this spring arrangement is to afford a relief when the pinchers have fully closed on the work and the needle has not completed its thrust. When the needle is withdrawn, the pinchers stand open and at their lowest position ready to grasp the work. Upon movement of the needle toward the work the pinchers are closed and also a slight movement is imparted to the rocker c' , which causes the pinchers to be elevated by reason of the fact that the movement of the bracket c^3 rectilinearly will produce motion in the rocker through the lever c^2 when the latter has passed a vertical central line embracing its pivot. When the pinchers are thus elevated, they are also moved out by the movement of the link f'' in the arc of a circle. Thus it will be seen that the pinchers have the effect of lasting the upper.

Operation of the stitch-forming and lasting devices above described is controlled by the attendant through a shipper-lever h , which has a handle h' conveniently located, and is connected with a clutch-pulley h^2 , rotating loosely on the shaft b and longitudinally movable thereon to engage it with and disengage it from the clutch member b' .

Passing on to the work-supporting and feeding devices, the letter i designates a turn-table, which is mounted on the platform a^2 and carries affixed to it a ratchet-wheel i' and also a diametrical slide-way i^2 . In the latter fits a slide i^3 , having swiveled to it a bracket or holder i^4 , between whose arms there is pivoted a last-support comprising a block i^5 , having divergent arms i^6 and i^7 , a sleeve j adjustable on the arm i^6 , a heel-pin j' pivoted between ears on said sleeve and having a lateral arm j'' recessed for engagement of an expansive spring x , and a toe-rest j^2 adjustable on the

arm i^7 . The last 3 fits on the heel-pin j and is pressed against the toe-rest by the spring x .

The above-described last-supporting jack 70 can be both turned and rocked endwise by the attendant, so that he can control its position as well as if he held it in his hands, as usual. This capability of the jack and the capability of universal movement of the support for the stitching and lasting devices together give the attendant such control of the machine as to conform it at all times to the contour of the shoe and cause the stitches to be taken close to the last at all parts of the 80 shoe.

Means are employed to impart to the jack both a rectilinear step-by-step feed motion in the direction of its length and a step-by-step rotary feed motion to round the heel and toe, 85 as follows: A lever k is pivoted on the platform a^2 so as to swing horizontally, and at its forward end it carries a spring-pressed pawl k' in engagement with the ratchet-wheel i' . At the opposite end the said lever carries a 90 roller-equipped pin, which engages a cam-groove in a cylinder k^2 on a shaft k^3 in bearings on the platform. It will be seen that rotation of the cam k^2 will produce step-by-step rotation of the turn-table. 95

A pitman m loosely embraces the stud i'' , on which the bracket i^4 swivels, and to the said pitman is jointed a rod m' , which is connected through a universal joint m^2 with the lower end of a lever m^3 , pivoted at its upper 100 end to the head a^3 . A segmental ratchet m^4 , pivoted to a pendent ear of said head, is connected by a rod m^5 with the lever m^3 , and an arm m^6 , pivoted on the journal of said ratchet, carries a spring-pressed pawl m^7 for engagement with the latter. The arm m^6 is connected by a link m^8 with a crank m^9 on the shaft b and receives a vibratory motion through this means. The vibratory motion of the arm causes the pawl to move the ratchet 110 step by step and the intermittent motion is transmitted through the connections described to the slide 13. 115

When the last is to move rectilinearly in stitching along the sides of the shoe, the turn-table is locked to prevent accidental rotation thereof, the lock being in the form of a pin or bolt n , which slides up through the platform and enters a socket in the turn-table. Of course, under this adjustment the 120 table-turning means are thrown out of operation. A single performance by the attendant unlocks the table, renders operative the table-turning means, and renders inoperative the devices which move the jack-carrying 125 slide, the arrangement for accomplishing this being of the following description: A treadle o is connected by an extensible link o' with a lever o^2 , which is pivoted centrally to a bearing on the under side of the platform a^2 and held up on the front side of its pivot by a spring o'' . The forward end of said lever is connected with the bolt n , and the rear end is connected with one arm of a bell-crank le- 130

ver o^3 , which occupies a plane transverse to the lever o^2 and has its vertical arm in engagement with a clutch-pulley o^4 , loose on the shaft k^3 and arranged to move longitudinally 5 to engage it with and disengage it from a clutch-disk o^5 affixed to the shaft. The lever o^2 carries affixed to it an upright tappet-rod p , which acts against one arm of a bell-crank-lever p' , whose other arm abuts the end of an 10 elongated plate p^2 , hung by a link p^3 from the pivot of the lever m^3 . The forward end of the plate p^2 is arranged to act against the pawl m^7 to disengage it from the ratchet and said forward end of the plate is supported by a 15 pin q fastened in the arm m^6 and engaging a slot in the plate. It will now be seen that depression of the treadle withdraws the bolt n , shifts the pulley o^4 into engagement with the clutch-disk o^5 , and throws the pawl m^7 out 20 of engagement with the ratchet m^4 .

The letter z designates the driving-shaft, which is mounted in an upward extension of the lower member of the column a and carries a pulley z' for receiving motion and two 25 other pulleys z^2 and z^3 , one connected by a belt z^4 with the pulley h^2 and the other being connected by a belt z^5 with the pulley o^4 . I employ a compensating arrangement for keeping the belts taut in the form of an arm y , pivoted 30 to the head a^3 and equipped with sheaves y' and y^2 , the belt z^4 being passed around the sheave y' and the two stretches of the belt z^5 being passed between the sheaves y^2 . This arrangement compensates for changes in the 35 relative positions of the pulleys, due to adjustment of the upper section of the column a .

The machine is intended to stitch the upper of the shoe to a lip of the inner sole, and in the particular style of shoe intended to be 40 operated upon this lip is formed by a marginal portion of one thickness of material, the inner sole being composed of two thicknesses of material secured together on a line somewhat back from their edges.

The general operation of the machine is as 45 follows: The last-jack having been properly adjusted and the last with the work upon it having been fitted on the jack, the stitching is to be commenced—say, for example, at the 50 toe and continued along one side to the heel. The parts are in the adjustment shown in Fig. 1, the turn-table being locked and the pawl m^7 being in engagement with the ratchet m^4 . The attendant, by using the handle g , brings 55 the stitching-head over the work, and the free marginal portion v' of the outer thickness of the inner sole v is engaged with the bifurcation of the guide d , while the upper w is inserted between the presser-foot c and the said 60 guide d and into the open pinchers. The jack is adjusted to bring that portion of the work where the stitch is to be taken as close as possible to the needle, and then by operating the lever h the attendant moves the pulley 65 h^2 into engagement with the clutch-disk b' , and thereby sets in operation the stitch-forming and lasting devices hereinbefore de-

scribed, and also the means for moving the jack-slide step by step in its slide-way. As the needle advances, the pinchers close on the 70 upper and move up and out, stretching said upper over the last. The needle penetrates the upper and the lip of the inner sole while the pinchers are holding the upper tight and the thread-guide engages the thread with the 75 needle, so that the latter in receding carries a loop of the thread with it for the stitch. As the needle recedes, the pinchers loosen their grip on the upper and move down and inward for a new hold, and while they remain open 80 the feed motion takes place, carrying the slide one step in the direction of its length. At the same time the thread-guide in its upward movement draws the stitch tight. When the heel is reached, the attendant depresses the 85 treadle o and the table i is turned half-way round step by step, while the stitching continues, after which half-rotation of the table the treadle is released and the rectilinear feed resumed to stitch the shoe along the other 90 side. The toe is rounded in the same way as the heel. It is to be noted that when the turn-table is rotated the segmental ratchet is released from the pawl and will be moved back to its initial position by reason of the jack- 95 last describing an orbit about the center of the table. As the work is fed the guide d acts as a plow in turning up the marginal portion of the outer thickness of the inner sole. Fig. 9 shows the position of parts just before 100 a stitch is taken.

What I claim as my invention is as follows:

1. In a machine for uniting uppers and soles of boots and shoes, the combination of a last-jack comprising a turn-table having a slide-way, a slide fitting said way, a holder horizontally swiveled to said slide, and a last-support on said holder; feed mechanism applied to the slide; and feed mechanism applied to the turn-table. 110

2. In a machine for uniting uppers and soles of boots and shoes, the combination of a last-jack comprising a turn-table having a slide-way, a slide fitting said way, a holder horizontally swiveled to said slide, and a last-support 115 pivotally mounted on the said holder to permit endwise tilting; feed mechanism applied to the slide; and feed mechanism applied to the turn-table.

3. In a machine for uniting uppers and soles 120 of boots and shoes, the combination of a last-jack comprising a swiveled member and a sliding member; feed-mechanisms for moving the sliding jack-member step-by-step and for turning the swiveled member step-by-step; 125 clutch mechanism for rendering the feed-mechanisms operative or inoperative; a lock for the swiveled jack-member; and a controlling device as a treadle operatively connected with the clutch mechanism and with the lock. 130

4. In a sewing machine for uniting uppers and soles of boots and shoes, the combination of a last-jack comprising an endwise tilting last-support and a swiveled holder therefor;

and stitch-forming devices on a universally movable head under control of the attendant.

5. In a sewing machine for lasting boots and shoes, the combination with stitch-forming devices including a vibratory needle; of lasting pinchers controlled in their action by the movements of the said needle.

6. In a sewing machine for lasting boots and shoes, the combination with stitch-forming devices including a vibratory needle and a reciprocating driver therefor, of lasting pinchers operatively connected with said driver whereby they are opened and closed by the same, connections between the vibratory needle and the pinchers whereby they are raised and lowered, and means for moving the pinchers laterally in their vertical movement.

7. In a sewing machine for uniting uppers and soles of boots and shoes, the combination

of a bifurcated guide for turning up and holding a lip of the sole, said guide having a transverse needle-opening, a bifurcated presser-foot arranged to press the upper against said guide, a side-rest for the last, a needle arranged to pass through the bifurcation of the presser-foot and the opening in the guide, a thread-guide on the outer side of the lip-guide, and lasting pinchers on the inner side of the latter.

In testimony whereof I have signed my name to this specification, in the presence of two subscribing witnesses, this 27th day of October, A. D. 1894.

WILLIAM C. COLLYER.
